UNITED STATES PATENT OFFICE.

LEWIS A. MAPEL, OF ST. LOUIS, MISSOURI, ASSIGNOR TO THE AUTOMATIC APPLIANCE COMPANY, OF ST. LOUIS, MISSOURI, A CORPORATION OF MISSOURI.

DESIGN FOR A STATUETTE.

53,042.

Specification for Design.

Patented Mar. 4, 1919.

Application filed September 3, 1918. Serial No. 252,495. Term of patent 3½ years.

To all whom it may concern:

Be it known that I, LEWIS A. MAPEL, a citizen of the United States, residing at the city of St. Louis and State of Missouri, have invented a new, original, and ornamental Design for a Statuette, of which the following is a specification, reference being had to the accompanying drawing, forming a part thereof.

The accompanying drawing is a front elevation of my new design.

I claim:

The ornamental design for a statuette, substantially as shown.

LEWIS A. MAPEL.
